L. H. WILLIAMS

GAME

Filed July 20, 1921

UNITED STATES PATENT OFFICE.

LEONARD HYLES WILLIAMS, OF BROOKLYN, NEW YORK.

GAME.

Application filed July 20, 1921. Serial No. 486,243.

To all whom it may concern:

Be it known that I, LEONARD H. WILLIAMS, a citizen of the United States, and resident of borough of Brooklyn, county 5 of Queens, State of New York, have invented certain new and useful Improvements in Games.

The object of this invention is to provide a game or game board and devices operable therewith and for amusement, and while this game board is similar in some respects to others, that have been produced, it has certain differences and advantages such as indicating means, means for making the boards more difficult of operation, calling for greater skill upon the part of the player and for making the game more attractive by double indication of the success and non-success of the player in the attempt to 20 master the game.

The following is what I consider a good means of carrying out the invention and the accompanying drawings should be referred to for a complete understanding of 25 the specification which follows:—

In the drawings:—

Fig. 1 is a side elevation partly in section of the game board.

Fig. 2 an end elevation thereof.

Fig. 3 a plan view.

Fig. 4 a view elevation partly in section of a part removed.

Fig. 5 an enlarged sectional view of a part removed.

Fig. 6 is a fractional view of a modification.

Similar reference numerals indicate like parts in all the figures where they appear.

This game or game board consists of a 40 platform 10 which may be of any dimension but which should be oblong and surrounding the platform is a rail or barrier arranged upon the sides and ends of the platform as shown at 11, 12, 13, 14. The 45 platform is provided with a plurality of perforations 15, and indicating marks are arranged adjacent to each perforation as shown at 16. Between the perforations and arranged as desired are a plurality of barriers 17, 18, etc., which tend to protect the perforations and to make the admission thereto somewhat more difficult.

Upon the platform I also provide a line 55 19, which I have marked as a foul line and behind which all play must be made, and secured to the platform and at one

end thereof is a cabinet 20, the front of which is closed by means of a glass 21. Within the cabinet 20 are a plurality of pockets 22 each supporting a plate 23 bearing a numeral or other designating mark and the numerals or marks upon the plates 23 correspond or coincide with the indicating marks upon the platform and adjacent to each perforation 15. Behind each plate 23 I arrange a lamp or illuminating means 24 each lamp electrically connected so as to be operated independently.

Within each perforation 15 is a plug 25 centrally disposed therein and adapted to be moved downward by the admission of an object into the perforation 15. The object employed is a ball as shown at 26 in Figure 5 and the edges of the perforation 15 may be countersunk as shown at 27 to produce a socket for the reception of the ball 26. Each plug 25 is supported upon the spring 28, one spring being provided for each plug and upon the spring I produce also a contact point 29 which is adapted to be moved into contact with a point 30 upon an adjustable screw 31. The adjustable screw 31 is supported in a U-shaped bracket 40, which is in turn secured to the under-side of the board 10 and in such position as to bridge over or span the perforation 15.

A wire 32 from a source of electrical supply may be connected to all of the springs 28 and away from each screw 31 should extend a lamp 24 in a cabinet 20. The other wire from a source of supply should be connected to the other side of each of the lamps 24 and when a ball entering one of the perforations 15 depresses the plug 25 and causes the contacts 29 and 30 to meet, the circuit will be closed through a lamp 24 and the lamp will be illuminated disclosing the figure carried by the plate 23 immediately in front of the lamp. If a plurality of balls are caused to enter perforations 15 the plurality of lamps will be illuminated and the result will show the double value of the perforations or sockets that have been filled with balls.

The glass 21 may be ground glass so that the figures upon the plates 23 do not become visible until they are illuminated by their respective lamps. The figures 16 may be of any nature and it is not necessary that the 110 numeral be here employed but obviously figures upon the plates 23 should correspond

with the figures adjacent to the perforations 15.

The indicator 20 may be arranged at the player's end of the platform and the platform 5 may be arranged in duplicate for competitive play such as indicated in Figure 6 where two platforms are shown at 34 and 35 and two indicators 36 and 37 are supported upon a single standard 38. This arrangement allows a ready comparison of the 10 scores of the players, but as here shown only five lamps are employed, the idea being limited to the number of balls and the number of perforations that will show indications. This arrangement of the game would 15 obviously demand greater skill.

If desired I may round out the corners or the sharp angles of the board by means of blocks shown at 39 and modifications 20 may be made within the scope of the appended claims without departing from the principle or sacrificing the advantages of the invention.

Having described my invention what I 25 claim is:

1. A game board having a plurality of perforations, a member adapted to be moved over said game board and into any of said perforations, barriers adjacent to said per-

forations and means within each of said 30 perforations for indicating the occupancy thereof, said means comprising a resiliently supported contact member and an adjustable contact member in the path of movement of the first said contact member and 35 means for supporting said adjustable member, comprising a U-shaped bridging member, spanning the perforation.

2. A game board having a plurality of perforations, a member adapted to be moved 40 over said game board and into any of said perforations, barriers adjacent to said perforations and means within each of said perforations for indicating the occupancy thereof, said means comprising a resiliently supported contact member and an adjustable contact member in the path of movement of the first said contact member and 45 means for supporting said adjustable member, comprising a U-shaped bridging member, spanning the perforation and a plug secured to said resiliently support contact member and entering the perforation and depressed upon the occupancy of said perforation by the member adapted to move 50 over said board.

LEONARD HYLES WILLIAMS.
